REPLACEABLE TOOTH FOR EXCAVATING IMPLEMENT AND THE LIKE

Thomas A. Ratkowski, Chicago Heights, Ill., assignor to The American Brake Shoe and Foundry Company, New York, N. Y., a corporation of Delaware

Application August 7, 1940, Serial No. 351,719

9 Claims. (Cl. 37—142)

The present invention relates to teeth for excavating implements and the like, and particularly to renewable teeth of such construction as to retain their sharpness during their normal period of usefulness.

Among the objects of the present invention is to provide a novel tooth for excavating implements and the like characterized by its ability to retain its sharpness during its normal period of usefulness.

The development in the art in respect to dipper teeth of such a construction as to retain their sharpness during normal use is fairly represented in the McKee Patent No. 1,395,048, wherein the structure provided was intended to assure a sharp tooth as the same progressively wore so as to retain the sharpness of the original tooth during its useful wearing life. Such structure is of particular value in that the tooth does not become dull or blunt during its progressive wear, thus resulting in a tooth having maximum efficiency throughout its life. These desirata insofar as the McKee structure is concerned, have not been experienced in actual practice for the reason that it was found that the marginal ribs, because of their relative proportion to the intervening panel space therebetween, did not wear as originally contemplated, so that after some wear had taken place on the tooth point the marginal edges of the tooth became blunt, requiring repair or replacement in order to provide an effective digging instrument. This lack of wear on the marginal ribs can undoubtedly be attributed to the fact that large particles of the material being excavated, upon contacting the said marginal ribs, tended to slough off or be directed into the relatively wide panel or trough between the ribs, thus decreasing the wear which might be experienced on the said ribs during the use of the tooth under actual digging operations.

The present invention has therefore been predicated upon a desire to form a tooth which will maintain its sharpness throughout its useful wearing life, the said structure being fundamentally characterized by a presentation of ribs at intervals throughout the width of the tooth such that the large particles of material will be supported between the ribs during their normal movement over the working surfaces of the tooth point so as to cause greater uniformity and evenness in the wear taking place throughout the width of the tooth to maintain the proper chisel or knife edge characteristic of the tooth in its original form and to maintain this relation of the wearing surfaces throughout its normal wearing period.

The tooth point characterizing the present contribution in the art is formed with its upper and lower wedge surfaces provided with a plural-

ity of relatively narrow elongated grooves extending from adjacent the apex of the wedge body longitudinally rearwardly and which grooves are defined marginally by relatively narrow ribs 5 to secure the uniform wear above referred to and to provide stiffening members reinforcing the tooth in a lateral direction to prevent bending of the tooth during actual use.

While the invention in its broadest aspect contemplates the fluted or serrated construction embodied in tooth structures of various designs, the invention, as specifically shown, is embodied in a tooth having divergent jaws forming a crotch therebetween and having rearwardly extending tangs providing attachment means for securing the tooth to a tooth base, the said fluted or serrated formation for the wedge surfaces extending rearwardly beyond the crotch to provide a sharp tooth during normal wear of the said tooth down to substantially the crotch thereof, and to further provide for normal and uninterrupted passage of the material into which the tooth is projected to facilitate loading of such material into the excavating implement to which these teeth are secured.

Other objects, features, capabilities and advantages are comprehended by the invention, as will later appear and as are inherently possessed thereby.

Referring to the drawing:

Figure 1 is a plan view of a dipper tooth embodying structure according to the present invention;

Figure 2 is a view in side elevation of the dipper tooth shown in Figure 1 of the drawings; and

Figure 3 is a view in section taken in the plane represented by line 3—3 of Figure 2 of the drawing.

Referring now more in detail to the drawing, an embodiment selected to illustrate the invention is shown as comprising a wedge body 2 having its apex 4 presented forwardly in digging position and including the upper and lower diverging wearing faces 6 and 8 extending rearwardly to provide the divergent jaws 10 and 12, respectively, spaced apart to form the crotch 14 defined laterally by the transverse walls 16 providing a socket for receiving a tooth base upon which the tooth is to be mounted in use. Extending rearwardly from the jaws 10 and 12 are the tangs 18 and 20, respectively, which provide therebetween a longitudinal slot 22 which receives the tooth base above referred to, these tangs 18 and 20 being provided with the aligned substantially rectangular formed openings 24 adapted to receive a key for attaching the tooth to the said base.

The present invention is directly particularly to structural features which adapt the tooth to retain its original sharpness during its normal

period of usefulness, and accordingly the wedge body 2 forming the tooth of the drawings has incorporated in the upper and lower wearing faces 6 and 8 a plurality of relatively narrow elongated grooves 26 laterally spaced throughout the width of the tooth and marginally defined longitudinally by the ribs 28, the said grooves 26 extending rearwardly longitudinally of the axis of the tooth and beyond the crotch formed by the spaced divergent jaws 10 and 12.

This serrated or fluted construction has the distinct advantage of providing bearing surfaces spaced sufficiently close together for the relatively large particles of material being excavated such that the said material during the normal projection of the tooth into the same has bearing engagement with the said ribs, causing substantially relative uniform wear over the ribs and the forwardly projecting part of the tooth therebetween and forming the bottom of said grooves such that the wear taking place over the forward end of the tooth causes said forward end to take the shape as indicated by dotted lines at 30, which formation conforms substantially to the diverging relation of the wearing surfaces adjacent the apex 4 before any wear has taken place on the tooth. This wear resulting from the ribs 28 as well as on the tooth point intermediate the same causes the tooth to retain its sharpness during its normal period of usefulness, and it has been found that such a contour for the forwardly presented end of the tooth maintains during progressive wear of the tooth rearwardly to substantially the crotch of said tooth so that sharpening, welding or otherwise repairing said tooth becomes unnecessary during its useful life. It is of course understood that as the tooth progressively wears to adjacent the crotch of the body, that it becomes necessary to replace the tooth, but because of the sharpness retained by the tooth during such wear, repair of said tooth becomes unnecessary to secure maximum performance thereof.

While I have herein described and upon the drawing shown an illustrative embodiment of the invention, it is to be understood that the invention is not limited thereto but may comprehend other constructions, arrangements of parts, details and features without departing from the spirit of the invention.

I claim:

1. A dipper tooth comprising a wedge-shaped body having at least one of its wedge surfaces formed with a plurality of grooves extending longitudinally of said body adapted to cause said tooth to retain its sharpness during its normal period of usefulness.

2. A dipper tooth comprising a wedge-shaped body having at least one of its wedge surfaces formed with a plurality of relatively narrow elongated grooves extending longitudinally of said body and defined marginally in a longitudinal direction by relatively narrow ribs adapted to provide for substantially uniform wear of the tooth throughout its width whereby the same retains its sharpness during its normal period of usefulness.

3. A dipper tooth comprising a wedge-shaped body having at least one of its wedge surfaces formed with longitudinal marginal ribs and one or more longitudinally disposed intermediate ribs forming a plurality of longitudinally extending grooves therebetween thereby adapting said

tooth to retain its sharpness during its normal period of usefulness.

4. A dipper tooth comprising a wedge-shaped body having its wedge surfaces formed with a plurality of grooves extending longitudinally of said body thereby adapting said tooth to retain its sharpness during its normal period of usefulness.

10 5. A dipper tooth comprising a wedge-shaped body having its wedge surfaces formed with a plurality of relatively narrow elongated grooves extending longitudinally of said body and defined marginally in a longitudinal direction by relatively narrow ribs adapted to provide for substantially uniform wear of the tooth throughout its width whereby the same retains its sharpness during its normal period of usefulness.

15 6. A dipper tooth comprising a wedge-shaped body having its wedge surfaces formed with longitudinal marginal ribs and one or more longitudinally disposed intermediate ribs forming a plurality of longitudinally extending grooves therebetween thereby adapting said tooth to retain its sharpness during its normal period of usefulness.

20 7. A dipper tooth comprising a wedge-shaped body provided with rearwardly extending jaws for securing said tooth to a tooth base, said body having its upper and lower wedge surfaces formed with a plurality of elongated grooves extending longitudinally of said tooth and defined marginally by relatively narrow ribs adapted to provide for substantially uniform wear of the tooth throughout its width whereby the same retains its sharpness during its normal period of usefulness.

25 8. A digging tooth for excavating implements, comprising a body portion in the form of a wedge with its apex presented forwardly in digging position and upper and lower diverging wearing faces extending rearwardly to provide spaced divergent jaws providing a crotch therebetween for receiving a tooth base upon which the tooth is to be mounted in use, a pair of tangs rearwardly extending from said jaws for attaching said tooth to said tooth base, said body having its upper and lower wedge surfaces formed with a plurality of elongated grooves extending longitudinally of said tooth and defined marginally by relatively narrow ribs adapted to provide for substantially uniform wear of the tooth throughout its width whereby the same retains its sharpness during its normal period of usefulness.

30 9. A digging tooth for excavating implements, comprising a body portion in the form of a wedge with its apex presented forwardly in digging position and upper and lower diverging wearing faces extending rearwardly to provide spaced divergent jaws providing a crotch therebetween for receiving a tooth base upon which the tooth is to be mounted in use, a pair of tangs rearwardly extending from said jaws for attaching said tooth to said tooth base, said body having its upper and lower wedge surfaces formed with a plurality of elongated grooves extending longitudinally from adjacent said apex rearwardly beyond said crotch and defined marginally by relatively narrow ribs adapted to provide for substantially uniform wear of the tooth throughout its width whereby the same retains its sharpness during its normal period of usefulness.
